6 Claims. (Cl. 260—172)

The present invention relates to dyestuffs.

It is always a desideratum in the dyestuff art to enrich the state thereof by the development and embodiment of new dyestuffs, especially such as are characterized by

superior fastness properties. A primary object of the present invention is thus to enrich the dyestuff art.

This object is realized, according to this invention, by the embodiment of a group of copperable trisazo dyestuffs which correspond to the formula

wherein x is hydrogen, methyl or chlorine, and y is methyl or ethyl.

These new dyestuffs are conveniently prepared by coupling 1 mol of tetrazotized 4,4'-diamino-3,3'-dialkoxy-1,1'-diphenyl with 1 mol of 2-hydroxybenzene-1-carboxylic acid or a derivative thereof which can couple and with 1 mol of the monoazo dyestuff obtained by the acid coupling of diazotized 5-nitro-3-amino-2-hydroxybenzene-1-carboxylic acid with 2-amino-5-hydroxynaphthalene-7-sulfonic acid.

The dyestuffs thus prepared dye textile fibers, especially cotton and fibers of regenerated cellulose, in violet shades

embodiments thereof. In the examples, parts are by weight; temperatures are in degrees centigrade.

Example 1

5 24.4 parts of 4,4'-diamino-3,3'-dimethoxy-1,1'diphenyl are tetrazotized and, while cooling with ice, are coupled on one side in a medium made alkaline with sodium carbonate with 13.8 parts of 2-hydroxybenzene-1-carboxylic acid. Upon completion of the formation of the resultant intermediate, the latter is coupled, preferably in the presence of 5-10% by volume of pyridine base mixture, with 44.8 parts of the monoazo dyestuff obtained by the acid coupling of diazotized 5-nitro-3-amino-2-hydroxybenzene-1-carboxylic acid with 2-amino-5-hydroxynaphthalene-7-sulfonic acid. The resultant dyestuff is isolated (e. g. by precipitation and filtering off) and dried.

The thus-obtained trisazo dyestuff, which corresponds to the formula

The chemical structure is a complex organic molecule with the following features:

- Top Left:** A benzene ring with an H_3CO (methoxy) group attached to the para position.
- Top Middle:** A benzene ring with an OCH_3 (methoxy) group attached to the para position.
- Top Right:** A benzene ring with an OH (hydroxyl) group attached to the para position.
- Middle:** A central benzene ring with an $\text{N}=\text{N}-$ group attached to the para position.
- Bottom Left:** A benzene ring with an $\text{HO}_2\text{S}-$ (sulfonamido) group attached to the para position.
- Bottom Middle:** A benzene ring with an NH_2 (amino) group attached to the para position.
- Bottom Right:** A benzene ring with an $\text{N}=\text{N}-$ group attached to the para position.
- Bottom Far Right:** A benzene ring with an NO_2 (nitro) group attached to the para position.
- Bottom Far Left:** A benzene ring with an HO (hydroxyl) group attached to the para position.
- Bottom Far Right:** A benzene ring with a COOH (carboxylic acid) group attached to the para position.

30 dyes cotton and fibers of regenerated cellulose, with good exhaustion capacity, in dull violet shades. Good fastness properties are obtained, and the shade darkened toward the black, by after-coppering. Thus, the fastness to hot washing of cotton dyeings, aftertreated with a

45 basic cation-active copper complex compound, is particularly good. This is true also of the fastness to light of dyeings on unwashed spun rayon which has been crease-proofed with melamine resin and then aftertreated with a cation-active copper complex compound, which may be basic.

Example 2

A very similar dyestuff, yielding dyeings similar to those aforescribed, is obtained when, while otherwise proceeding as described in Example 1, the 24.4 parts of 4,4'-diamino-3,3'-dimethoxy-1,1'-diphenyl are replaced by 26.8 parts of 4,4'-diamino-3,3'-diethoxy-1,1'-diphenyl. The dyestuff thus obtained corresponds to the formula

of superior fastness properties which, moreover, can be 70 enhanced by after-coppering.

The following examples illustrate presently-preferred

Example 3

hydroxybenzene-1-carboxylic, and otherwise proceeding as described in the said example, the dyestuff of the formula

is obtained, the properties of which are similar to the dyestuff according to Example 1.

Example 4

By replacing the 2-hydroxybenzene-1-carboxylic acid in Example 1 by an equivalent quantity of 4-methyl-2-hydroxybenzene-1-carboxylic, and otherwise proceeding as described in the said example, the dyestuff of the formula

is obtained, the properties of which are similar to the dyestuff according to Example 1.

Example 5

By replacing the 2-hydroxybenzene-1-carboxylic acid in Example 1 by an equivalent quantity of 3-chloro-2-hydroxybenzene-1-carboxylic acid, and otherwise proceeding as described in the said example, the dyestuff of the formula

is obtained, the properties of which are similar to the dyestuff according to Example 1.

Example 6

10 parts of cotton are entered into a dyebath contain-

process, 3-4 parts of Glauber salt are added in the form of a concentrated aqueous solution. Upon completion

of the dyeing operation, the material is allowed to cool in the bath down to 50° in the course of 15-20 minutes, after which the material is rinsed. It may then be subjected to aftertreatment with copper sulfate or with a cation-active copper complex compound, which may e. g. be a basic compound.

The aftertreatment with copper sulfate is carried out as follows: The rinsed cotton material is added to a fresh

bath containing 300 parts of water of 70° and 0.3 part of copper sulfate. The bath is held for half an hour at 70°, then the material is rinsed and dried.

The aftertreatment with a cation-active copper complex compound is carried out by adding the rinsed cotton material to a fresh bath containing 300 parts of water and 0.3 part of e. g. the copper complex compound of the condensation product of diethylene triamine and di-cyanodiimide (obtainable f. i. according to the process of

the Swiss Patent No. 261,051), holding the bath for half an hour at 70° and rinsing and drying the material.

Having thus disclosed the invention, what is claimed is:

1. A trisazo dyestuff which corresponds to the formula

wherein x stands for a member selected from the group consisting of hydrogen, methyl and chlorine, and y stands for a member selected from the group consisting of methyl and ethyl.

2. The trisazo dyestuff which corresponds to the formula

ing 300 parts of lime-free water at 50°. Then a concentrated aqueous solution, which contains 0.8 part of any one of the aforescribed dyes, is added to the dyebath and the latter is heated to boiling within a 30-minute period, after which it is maintained at boiling temperature for 15 minutes. In the course of the dyeing

65

3. The trisazo dyestuff which corresponds to the formula

4. The trisazo dyestuff which corresponds to the formula

5. The trisazo dyestuff which corresponds to the formula

6. The trisazo dyestuff which corresponds to the formula
